W. F. BYRAM & R. P. PHRONEBARGER.
CURRENT SUPPLY SYSTEM FOR ELECTRIC RAILWAYS.
APPLICATION FILED JUNE 24, 1914.

1,134,371.

Patented Apr. 6, 1915.

Fig. 1

Fig. 3: A side view of a vertical assembly. It features a central vertical rod (14) with a flared top (12). A horizontal plate (11) is attached to the top of the rod. A spring (18) is wound around the rod, with its ends attached to the plate (11) and a base plate (21). The base plate (21) is supported by a central screw (23) and rests on a base (10). The base (10) is secured to a base plate (15) which is bolted to a horizontal surface (16). Other labeled parts include 4, 8, 9, 7, 6, 13, and 22.

Fig. 4: A top-down view of a circular base. It shows a central circular component (22) with a textured or ribbed surface. Around this central component are several smaller parts labeled 8, 6, 7, 11, 13, and 18. The entire assembly is supported by a base plate (21).

UNITED STATES PATENT OFFICE.

WILLIAM FLOYD BYRAM AND ROBERT PINK PHRONEBARGER, OF CHARLOTTE, NORTH CAROLINA.

CURRENT-SUPPLY SYSTEM FOR ELECTRIC RAILWAYS.

1,134,371.

Specification of Letters Patent.

Patented Apr. 6, 1915.

Application filed June 24, 1914. Serial No. 847,098.

To all whom it may concern:

Be it known that we, WILLIAM FLOYD BYRAM and ROBERT PINK PHRONEBARGER, citizens of the United States, residing at Charlotte, in the county of Mecklenburg and State of North Carolina, have invented certain new and useful Improvements in Current-Supply Systems for Electric Railways, of which the following is a specification, 10 reference being had to the accompanying drawings.

This invention relates to an improved current supply system for electric railways, and has for its primary object to provide cheap, 15 durable, and practical means for supplying the electric operating current to the motor carried by a car.

In its more specific aspect, the invention contemplates the provision of stationary 20 electrically charged contacts arranged in spaced relation between the rails, and improved means for entirely insulating said contacts from the rail ties, such insulating means also affording a protection for 25 pedestrians and preventing accidental engagement of a person with said charged contacts, thus rendering the device entirely safe to the general public in practical use.

The invention has for a further general 30 object to improve the construction of such devices so as to render the same highly efficient and reliable in practical use, and admit of the installation of my improved system in electric railways at a minimum expense.

35 With the above and other objects in view, the invention consists in novel features of construction, combination, and arrangement of parts as will be hereinafter referred to and more particularly pointed out in the specification and claims.

For a full understanding of the invention, reference is to be had to the following description and accompanying drawings, in which—

45 Figure 1 is a side elevation showing the general construction and arrangement of the parts of our invention in its preferred form; Fig. 2 is a top plan view of a single track, the conducting plate carried by the car being engaged with the adjacent insulating contacts mounted upon the rail supporting ties; Fig. 3 is an enlarged section taken on the line 3—3 of Fig. 2; and Fig. 4 is a section taken on the line 4—4 of Fig. 3.

55 Referring in detail to the drawings, 5

designates the parallel track rails, and 6 spaced ties upon which said rails are mounted in the usual manner. Upon certain of the ties 6 in proper spaced relation, the vertically disposed contact bolts 7 are mounted. 60 These bolts extend upwardly above the ties and are sheathed in the insulating standards 8. These standards are of general cylindrical form and are provided upon their lower ends with suitable attaching ears 9 65 whereby they may be rigidly secured upon the ties. A sleeve of insulating material indicated at 10 is also arranged around the bolt 7 in the opening formed in the tie. The upper end of each standard 8 is cut away 70 upon its inner side as shown at 11 so that the upper end of the bolt will be exposed. This cut-out or recessed portion of the insulating standard, however, produces a curved cap or crown 12 which extends over 75 the upper end of the bolt and beyond the recessed side of the standard, said crown or cap having a maximum diameter greater than the diameter of the body of the standard. Upon the bolt 7 a stop collar 13 is secured which rests upon the lower end wall of the recess 11 of the standard and prevents 80 downward movement of the bolt.

The lower end of the contact bolt 7 extends below the tie 6, and is provided with 85 an opening indicated at 14 through which the end of the current supply wire 15 is loosely engaged. This lower end of the contact bolt is threaded to receive a clamping nut 16 whereby the wire may be adjustably 90 and removably held in connection with the bolt.

Upon the truck frames of the car 17 longitudinally extending circuit closing shoes 18 are mounted. Each of these shoes is made 95 up of a plurality of sections connected together by bolts 19 so that when one section wears out, it may be readily removed and replaced by another section. This shoe is of sufficient length to extend between and engage with any two of the contact bolts 7 mounted upon the ties, and the ends thereof are rounded or curved as shown at 20. To the inner longitudinal edge of the circuit closing shoe at spaced points arms 21 are 105 secured, to each of which a lead wire 22 extending to the motor controller is connected. Coil springs 23 are connected to each of these arms at one of their ends, the other end of the springs being seated in suitable 110

insulating bearings which are carried by the truck frame. These springs act to yieldably hold the outer longitudinal edge of the shoe in engagement with the threaded contact bolts 7.

Having above described the construction and arrangement of the several parts of our invention, its operation will be understood as follows. The circuit closing shoes 18 are 10 at all times engaged with one of the contact bolts 7, and before the shoe moves out of engagement with one of said bolts, the opposite end of the shoe is engaged with the adjacent bolt, thus insuring the continuity 15 of current to supply the propelling motor. It will be seen that by yieldably mounting the shoe upon the truck frame, the same will be forcibly held in engagement with one of the contacts when the car moves upon a 20 curve in the line of track. As the contact bolts are completely insulated, except upon their inner sides and at their upper ends, which portions, however, are covered by the crown pieces of the insulating standards, liability of persons or cattle coming into contact with the charged bolts is practically 25 wholly eliminated. Our improved current supply system for railways is very reliable and efficient in practical use, and owing to 30 its extreme simplicity may be installed at comparatively small cost.

While we have above described the preferred form, construction, and arrangement of the several elements employed, it will be 35 understood that the device is, nevertheless, susceptible of considerable modification therein, and we therefore reserve the privilege of resorting to all such legitimate changes as may be fairly embodied within 40 the spirit and scope of the invention as claimed.

What is claimed is:

1. In a current supply system for electric railways, spaced vertically disposed contact 45 members arranged between the track rails, an insulating standard for each of said contact members extending through and secured

to the rail tie, said standard being recessed upon one side to expose the contact member and having a convex head overhanging said recess, means secured to the contact and engaged with the base of the recess to prevent longitudinal movement of the contact member with respect to the insulating standard, the lower end of said member projecting below the rail tie and being connected to a source of current supply; in combination with a contact shoe yieldably mounted upon the truck frame of a car and of greater length than the distance between any two 60 adjacent contacts whereby said shoe will at all times be engaged with one of the contact members.

2. In a current supply system for electric railways, a series of vertical contact members arranged between the track rails, insulating standards secured to the rail ties within which said contact members are disposed, the upper end of each of said standards being cut away on one side to expose the upper end of the contact member and provide an overhanging protecting crown, a collar secured upon the contact member to hold the same against longitudinal movement through the insulating standard, the lower end of said member being connected to the source of current supply, in combination with a contact shoe yieldably mounted upon the truck frame of the car and of greater length than the distance between 80 any two adjacent contacts whereby said shoe will at all times be engaged with one of the contact members.

In testimony whereof we hereunto affix our signatures in the presence of witnesses. 85

WILLIAM FLOYD BYRAM,
ROBERT PINK X PHRONEBARGER.
